UNITED STATES PATENT OFFICE

JOHN EDWARD LEARY, OF FITCHBURG, MASSACHUSETTS, ASSIGNOR OF ONE-HALF TO
EDWARD J. CROWSON, OF FITCHBURG, MASSACHUSETTS

COMBINATION LOCK

Application filed June 21, 1927. Serial No. 200,440.

The present invention relates to locks of the permutation type, and is particularly adapted for use where a handle or knob is employed for operating the latch.

5 It is an important object of the invention that the spindle upon which the handle is mounted is made slidable with respect to the other portions of the lock and closures, whereby a very simple and practical locking structure may be provided.

10 The invention may be applied to latch structures already in use and without any material change in the closures with which it will be used.

15 It is a further important feature of this invention that all of the operating parts are enclosed and are so positioned that a minimum of wear will result. In other words, the locking elements, as well as the 20 portion of the stem with which they are engaged, is concealed by being suitably housed whereby dirt and other matter which might tend to clog the lock are prevented from entering the essential working parts.

25 Referring to the drawings:

Figure 1 is a front view showing the structure in place upon a closure.

Figure 2 is a rear view.

Figure 3 is a sectional view showing the 30 invention with the lock in unlocked position.

Figure 4 is a similar view showing the invention with the lock in locked position.

Figure 5 is a view partly in section, of the 35 operating lever which serves to actuate the latch.

Figure 6 is a sectional view of part of the lock structure.

Figure 7 is a longitudinal section of the 40 lock structure, and

Figure 8 is a detail view of the handle stem.

In the drawings I have illustrated my invention in one of its embodiments as applied to the usual automobile door locking mechanism.

45 10 indicates the door, and 11 the opening therethrough for receiving the handle stem or spindle 12 to which is attached, in any suitable manner, a handle 13.

50 The construction of the handle stem or

spindle will now be described. It will be observed that at one end it is provided with a circumferential groove 14. Adjacent this groove the stem or spindle is squared as shown in 15 in Figures 2 and 3. Extending 55 within the squared portion and on one side thereof is a groove 16 communicating with the groove 14 and terminating at its opposite end within the squared portion. The squared portion is of less diameter than the 60 adjacent barrel of the stem, and adjacent the opposite end of this barrel portion is provided a relatively large circumferential groove 17. A second circumferential groove 18 is formed in the handle stem or spindle 65 as shown, and the intermediate portion of the stem is provided with a longitudinal groove 19 communicating with the grooves 17 and 18.

The lock structure is attached to the closure and positioned through the medium of a facing member 20 as shown in Figures 1, 3, 4 and 7. This facing member is attached to the outside of the door as shown in Figure 1, and is preferably segmental.

70 Referring to Figures 3, 4 and 7 it will be seen that the segmental member is provided with an opening 21 for the passage of the spindle 12 and concentric with said opening and in the front face of the segmental member is provided a circular recess 22. This recess is relatively deep and acts as a 75 housing.

The segmental member is provided with 80 circumferential openings and one wall of its recess is cut away. Frictionally positioned through the said openings is a pin 23 which has a portion of its length exposed within the recess 22 through the cut away portion in the wall of the recess. The purpose of this will be presently described, reference being had to Figures 2, 3, 6 and 7.

85 Mounted upon the spindle 12 is a tumbler member 24, as shown in Figure 7. This tumbler member is provided with an integral shoulder 25 at one end and at its opposite end is provided with a circumferential groove 26. It will here be stated 90 that as shown in Figures 6 and 7, the outer tumbler is naturally positioned in the recess 100

22 of the segmental member and is maintained in position therein by the engagement of the pin 23 having a portion of its length disposed through a cut away portion in the recess 22 and engaging in the circumferential groove 26 of the outer tumbler 24. This will permit the outer tumbler to be rotated with respect to the segmental member while maintaining the two members against longitudinal movement with respect to each other.

This will be understood upon reference to Figure 7 as well as Figures 2 and 3.

The tumbler 24 has a relatively large bore and interiorly thereof at one end is cut away to provide a circumferential groove 27. The grooves 26 and 27 of the tumbler member are preferably concentric, although this is not necessary.

It will be noted that the tumbler member is provided with an opening 28 for a purpose which will be later described.

As stated, the tumbler member is provided with a relatively large bore within which is received the inner tumbler 29. Referring to Figure 7, it will be seen that the inner tumbler is housed also for a portion of its length within the recess 22 of the segmental member. This inner tumbler is of smaller diameter at one end where it is threaded, as shown at 30. At its opposite end said inner tumbler is provided with an opening 31 which is threaded to receive a pin 32. This pin has its inner end projecting beyond the inner periphery of the tumbler 29, as shown at 33. The pin 32 by means of its projecting end 33 serves to maintain the inner tumbler in sliding position upon the spindle, the said pin engaging in the grooves 17, 18 and 19 for this purpose.

It will be seen that in this manner the inner tumbler cannot be unseated since the projecting end of pin 32 will be guided within said grooves, or relative movement of the shank and tumbler will be controlled. The stop shoulder 25 on the outer tumbler, it will be seen, engages the shoulder 34 at the threaded end of the inner tumbler to maintain the tumblers in proper position.

It will be noted that the inner tumbler is provided with a second opening 35 for a purpose which will also be described in connection with the opening 28 in the outer tumbler.

Threaded upon the portion 30 of the inner tumbler is a ring member 36 which is secured in fixed position to said inner tumbler by means of a screw 37, as shown, with its adjacent end abutting the end of the outer tumbler. Secured to the handle stem in fixed position adjacent the handle is a second ring member 38 which is held fixed to the handle by means of a screw 39. The parts are shown in their relative positions in Figures 3 and 7.

As previously stated, the outer tumbler is positioned within the recess in the segmental member and may have rotary movement therein with respect to said member by reason of the engagement of the pin 23 in the groove 26. The inner tumbler may also have rotary movement within the outer tumbler by reason of the engagement of the projecting portion of the pin 32 within the grooves 17 and 18 of the spindle. It will also be seen that when the spindle has its groove 19 positioned in alignment with the projecting end of the pin 32 on the inner tumbler, that said spindle may be slid past the pin by reason of its groove 19.

Disposed in the circumferential grooves 17 and 18 of the handle spindle is a detent or ball 40. This ball cooperates with the openings 28 and 35 in the tumblers as well as with the internal groove 27 in the outer tumbler. As previously stated, the handle is adapted to slide with respect to the segmental member and closure, and the associated tumblers 24 and 29 and ring member 36. When the two openings 28 and 35 are in alignment, they provide a sufficient depth so that the ball may ride therein over the spindle of the handle, that is, the greatest diameter of the spindle may slide freely with respect to the tumblers.

Referring to Figures 2 and 5 wherein the device is shown applied to an automobile door, it will be seen that the usual interior operating lever 41 is provided for releasing the latch 42, the said lever being acted upon by a spring projected member 43. The end of the spindle opposite the handle is extended through the door or closure 10 and there is fitted to its inner end an operating lever 44. This operating lever is provided with a squared opening 45 at one end, and at its other end, is forked, as shown at 46 to engage the operating lever 41. The lever 44 is secured to the shank by means of a pin 47 having its end 48 projecting into the circumferential groove 14.

It will be understood that the levers 41 and 44 are aligned with respect to each other so that the spindle is adapted to slide within the squared opening of the lever 44.

This sliding movement is permitted by reason of the pin 47 when the door is unlocked, engaging in the groove 16 whereby the squared opening of the lever 44 will slide onto the squared portion 15 of the spindle and turning of the handle will operate the lever 44 to throw the lever 41 and release the latch so that the door may be opened.

The spindle when withdrawn from the squared opening, to the limit of its movement, brings the circumferential groove 14 in alignment with the pin 47 so that turning of the handle will have no effect upon the operating lever except the parts will rotate.

relative to each other. This is the condition when the device is locked.

The segmental member is provided with a fixed indicator, while the rotating outer 5 tumbler is provided with a series of numerals or letters as is also the ring 36 which rotates the inner tumbler. The ring 38 which is fixed to the handle, preferably 10 is likewise provided with a plurality of numerals or letters depending, of course, upon the nature of the combination.

When it is desired to lock the device, the numerals or letters upon the rotating tumblers are brought into a predetermined relation with the fixed indicator on the segmental member and the particular number 15 or letter upon the fixed ring 38 which has been set. It will be understood that the fixed ring can be adjusted for various combinations upon the spindle by means of the screw 39. In this position the handle shank 20 can be slid forward releasing the lever 44, as previously described.

In order to unlock the device, presuming 25 that the handle has been pulled out, it will be noted that the pin 31 is within the groove 17 while the ball 40 is also in the said groove and in the hole 35 of the inner tumbler. It is also presumed that the inner tumbler 30 has been given rotation so as to bring the pin 31 away from the slot 19 and in the groove 17. In this position the tumblers are freely rotatable, but the inner tumbler will not permit the shaft to slide because 35 the pin cannot pass out of the groove 17 unless it is properly brought in alignment with the groove 19.

Also the outer tumbler having been given 40 a twist, its opening 28 is out of alignment with the opening 35 and groove 17 so that the ball cannot project out of the opening. In this position, as stated, the outer tumbler is rotated with respect to the inner one, but 45 cannot move longitudinally with respect to the inner tumbler because although the ball is engaged in the groove 17 and opening 35 of the inner tumbler, it also engages within the groove 28 on the inner circumference of the outer tumbler. Thus while the outer 50 tumbler can rotate with respect to the inner tumbler, the engagement of the ball in the groove 28 of the outer tumbler serves to prevent relative longitudinal movement.

It is, therefore, necessary to bring the 55 several tumblers into proper position in accordance with the combination, in which position the pin of the inner tumbler will be in the groove 17 opposite the longitudinal groove 19. At the same time the openings 60 27 and 35 in the inner and outer tumblers will be in alignment. Then it is only necessary to push the handle in whence the pin 32 will slide through the groove 19 as the handle is pushed in and the ball will pass up 65 into the openings in the inner and outer

tumblers which are deep enough to contain it so that the handle may be slid completely forward to bring the squared opening of the lever 44 into engagement with the squared end of the spindle.

In this position the pin 31 is in the groove 18 and by rotating the inner tumbler and the outer tumbler with respect to it, the parts will be in a position where they will remain 70 unlocked until further required. It will be seen, therefore, that the invention will not interfere with operation of the door from the inside in either its locked or unlocked position and that it may be so fixed when in unlocked position as to permit the door to 75 be used as usual.

In order to lock the door, that is, so that it cannot be operated from the outside, the combination is set as before bringing the pin 32 into alignment with the groove 19 and the ball receiving openings are in alignment 80 over the groove 18. In this position the spindle may be slid out to disengage the lever 44 from the squared portion of the shank and permit its free rotary movement 85 in the groove 14 by reason of the pin 47.

In this position the pin 32 is, as previously described, in the groove 17 and the ball receiving openings are in alignment, but the ball is received within the groove 17 90 and the opening of the adjacent inner tumbler. Thus, as in the unlocked position the two tumblers may be rotated with respect to each other to bring the ball receiving 95 openings out of alignment and to bring the pin 31 away from the groove 19.

The invention is a very simple one and while I have illustrated it in connection with 100 an automobile door, I do not wish to be limited to this application because the invention may be applied in practically every case where a lock structure is needed.

What I claim is:

1. A locking structure comprising a stem, 110 relatively movable tumblers associated therewith, one of said tumblers carrying an element adapted to lock the stem against sliding movement in one position of the element, a second loosely carried element associated with said tumblers and adapted to prevent sliding movement of the stem relative to said tumblers in one position of said second element, said elements being releasable for movement with relation to said stem whereby said stem may have sliding movement 115 with respect to said tumblers.

2. A locking structure comprising a stem, 120 tumblers associated therewith and rotatable thereon relative to each other and to the stem, one of said tumblers carrying an element cooperating with said stem, a second element cooperating with said stem and tumblers, the other tumbler having an opening 125 cooperating with an opening in the first 130

mentioned tumbler whereby when the element carried by said first mentioned tumbler is in position relative to said stem and the openings in the respective tumblers are in alignment, the said elements will permit sliding movement of the stem.

3. A locking structure comprising a stem, tumblers associated therewith, one of said tumblers having an opening therein and carrying an element cooperating with said stem, the other tumbler receiving the first mentioned tumbler and being provided interiorly with a groove, an element cooperating with said stem and tumblers and in one position of said last mentioned element preventing sliding movement of the stem with relation to the tumblers by reason of the engagement of the element in said groove, said second mentioned tumbler having an opening cooperating with said first mentioned opening whereby when the first mentioned element is in proper position relative to said stem and said openings are in alignment, sliding movement of the stem with relation to the tumblers will be permitted.

4. A locking structure comprising a stem, locking means associated therewith for permitting sliding movement of the stem in one position of said means and preventing sliding movement in another position thereof, one end of the stem being provided with a groove extending longitudinally thereof and communicating with a second groove circumferentially of the stem, an operating lever associated with said end of the stem and carrying a pin which is guided in said grooves whereby in one position of its sliding movement the stem is freely movable with respect to said lever.

5. A locking structure comprising a stem, locking means associated therewith for locking the stem against sliding movement in one position of said means and permitting sliding movement of the stem in another position thereof, said stem being provided with a squared portion at one end, and a lever adapted to actuate a latch movable with the stem when said stem is rotated in one position of its sliding movement and freely movable with relation to said stem in another position of the sliding movement thereof whereby the latch will not be actuated.

6. A locking structure comprising a stem having grooves therein, tumblers arranged on said stem adjacent said grooves, elements associated with said tumblers and cooperating with said grooves to prevent longitudinal movement of the stem with relation to said tumblers, and grooves formed in said stem communicating with each other and extending in opposite directions, and an operating lever carried by the stem and hav-

ing means engaging in said last mentioned grooves.

7. A locking structure for doors comprising a spindle and latch means associated therewith, a handle at one end of the spindle exteriorly of the door, an operating lever interiorly of the door and associated with said latch means, a second lever associated with said spindle and adapted to engage said first lever to retract said latch means, and locking means associated with said spindle for selectively permitting and preventing operation of said second lever by the handle exteriorly of the door, the said first lever being at all times operatively associated with the latch means to permit opening of the door interiorly thereof.

In testimony whereof I have hereunto set my hand.
